UNITED STATES PATENT OFFICE.

JOHN J. LARSON, OF CLARION, IOWA.

HORSE-EVENER.

SPECIFICATION forming part of Letters Patent No. 795,140, dated July 18, 1905.

Application filed September 30, 1904. Serial No. 226,702.

To all whom it may concern:

Be it known that I, JOHN J. LARSON, a citizen of the United States, residing at Clarion, in the county of Wright and State of Iowa, have invented new and useful Improvements 5 in Horse-Eveners, of which the following is a specification.

This invention relates to draft-equalizers generally, and more particularly to those used 10 in plowing and in reaping and binding, and cutting grass, &c.

While it will appear plain from the description hereinafter given that my invention may be embodied in various forms of means, that 15 shown in the drawings is one of the best now thought of by me, and as it serves well to make clear the construction and operation of the said invention the description will be closely confined to the said drawings without 20 any purpose of so limiting it.

As shown, the invention is adapted for the employment of three, four, or five horses, and its object is, first, to equalize the draft so as to draw the machine straight ahead irrespective of the position of the horses; second, 25 to enable five horses to be hitched side by side, giving room for one horse to walk in the furrow and the others on the solid unplowed ground; third, to enable four horses to be 30 hitched to the evener so as to draw a reaper and binder in proper line, the horses walking side by side, with none working "in the grain;" fourth, to provide various improvements in the construction and arrangement of 35 parts to secure betterments in the mode of operation of the contrivance, as will clearly appear from the description and claims.

Reference is to be had to the accompanying drawings, and to the symbols of reference 40 marked thereon, forming a part of this specification, the same symbols designating the same parts or features, as the case may be, wherever they occur.

Of the said drawings, Figure 1 is a perspective view of the invention as it may be constructed and arranged for the employment of five horses and in which the vertical extension is pivotally and adjustably connected to the beam extension, shown, for example, to 45 consist of two plates attached together at

their ends and passing outside the main beam or tongue. Fig. 2 is a perspective view of the invention, showing it as equipped for four horses and showing an instance in which the vertical extension is not pivotally connected 55 with the means drawn upon, but turning on a pivot connected with the same. Fig. 3 is a perspective view of the lateral draft-beam and the pendent casting or vertical extension for connecting it with the plow-beam or other 60 means drawn upon through the intermediaries shown and described. Fig. 4 illustrates a modified form of means for securing the plow-beam A with the vertical casting b.

As before stated, the invention is designed 65 for use on reapers, gang-plows, and farm implements generally that are to be drawn by horses, so that whether we consider the means shown as connected with a plow-beam or means for drawing a reaper or binder it will 70 make the application of the invention to other uses so plain that no reference thereto need be made.

In the drawings, A designates a plow-beam 75 or reaper-tongue, and a is a draft-beam provided at its inner end with a vertical casting b, which is adapted to extend between two forwardly-extended castings e f, Fig. 1, and to be connected thereto by a bolt passed through the holes c. There being a series of 80 these holes c in the casting b it will be plain that it may be adjusted through these means in higher or lower position in the beam or tongue A or through intermediaries with the said tongue. As shown in Fig. 2, the casting 85 b is passed through a simple slot formed in the front end of the beam, and it is held in place by a pivot or bolt c' (see Fig. 2) in the eye-casting n, secured beneath the beam. Having reference again to Fig. 1, the castings e f 90 at their rear ends are connected to a draft-plate a' by a bolt g, and it will be seen that under the construction shown in this figure it may be adjusted at a higher or lower level through the medium of the series of holes 95 formed in the said draft-plate. There may be two draft-plates connected with and extending forward from the end of the beam A, one on each side thereof, as shown in Fig. 1, in which case castings d e will be pinned or 100

bolted to the draft-plates a' a' and extend forward on opposite sides of the vertical casting b , to which they may be bolted. The brace f , connected at one end to the casting 5 d , is connected at the other end to the draft-plate, to which the casting d is secured, and serves as additional support to the latter. It will also be noted that the said two plates, which are connected at their ends, form an 10 extension to the main beam or tongue, pass outside the said tongue. Should a single casting be employed to connect the draft-plates with the vertical casting b , the latter may be modified in construction, as shown in Fig. 4, 15 in which it is shown as provided with a slot c' , and the single casting d' extended therethrough and bolted thereon. h is an extension-piece connected with the lower end of the vertical casting b and projecting laterally 20 therefrom, and the draft-bar i is connected with the said casting at a point corresponding substantially with its longitudinal center by means of a clevis j , and a doubletree o is likewise connected at the outer end of the draft-bar i , while swingletree p p' are connected to the ends of the doubletree o through the medium of clevises and a swingletree p^2 has a clevis connection with the inner end of the draft-bar i . In Fig. 1 I have also shown the 25 draft-bar a as having a doubletree k , connected with its outer end by means of a clevis l , and swingletree p^3 p^4 as having a clevis connection with each end of the doubletree k . Under this construction it will be seen that five 30 horses may be used in the draft of the machine or farm implement, (say, for example, a plow,) and that by a proper adjustment of the parts the line of draft will be from the pivotal point c straight forward. The ex- 35 tension-piece h in this case performs an important part in securing equalization of draft on the pivot c .

By the construction shown in Fig. 2 it is intended to hitch but one or two horses to 40 the vertical casting b , which may be accomplished by means of a doubletree or swingletree.

tree, and which is connected by a clevis directly to the said vertical extension b . In this case, as well as the former, the draft will be directly forward, as will be indicated by 45 the lead-lines leading to the reference-letter b in Figs. 1 and 2.

It will be understood, of course, that all of the parts requiring to be made adjustable will be so formed, and that adjustments will be 50 made in accordance with the exigencies of all cases, and, furthermore, that all of the parts will be originally made to correspond with the strength required of them, as well as to the demands under which they may be put, as 55 length, &c.

I claim—

1. The combination, with the draft-means, and its vertical extension, of the main beam or means drawn upon, the said vertical extension being pivotally connected to the latter means.

2. The combination, with the main tongue or beam, of the lateral beam and the vertical extension attached to the inner end of the latter, the said vertical extension being pivotally connected with the main tongue or beam.

3. The combination, with the main tongue or beam, of the lateral beam, and the vertical extension attached to the inner end of the latter and provided on its lower portion with a horizontal extension, the said vertical extension being pivotally connected with the main tongue or beam.

4. The combination, with the main tongue or beam, of the lateral beam and the vertical extension attached to the inner end of the latter, the said vertical extension pivotally and adjustably connected with the main tongue or beam.

In testimony whereof I have signed my name to this specification in the presence of two subscribing witnesses.

JOHN J. LARSON.
